Primary Examiner — Derrick Holland*Assistant Examiner* — Lauren Calve(74) *Attorney, Agent, or Firm* — Kimberly-Clark Worldwide, Inc.**CLAIM**

We claim the ornamental design for a wiping substrate dispenser, as shown and described.

DESCRIPTION

FIG. 1 is a perspective view of a wiping substrate dispenser;
FIG. 2 is a side elevation view thereof;
FIG. 3 is a side elevation view thereof;
FIG. 4 is a front plan view thereof; and,
FIG. 5 is a back plan view thereof; and,
FIG. 6 is a top plan view thereof.

The broken lines shown in FIG. 5 represent unclaimed subject matter and form no part of the claimed design.
